UNITED STATES PATENT OFFICE.

WALTER R. THATCHER, OF OSKALOOSA, IOWA.

OIL-GAS BURNER.

1,122,817.

Specification of Letters Patent. Patented Dec. 29, 1914.

Application filed January 19, 1914. Serial No. 813,006.

To all whom it may concern:

Be it known that I, WALTER R. THATCHER, a citizen of the United States, residing at Oskaloosa, in the county of Mahaska and State of Iowa, have invented a new and useful Oil-Gas Burner, of which the following is a specification.

The invention relates to improvements in oil burners.

10 The object of the present invention is to improve the construction of oil burners, and to provide a simple, practical and inexpensive oil burner of strong and durable construction designed for use in stoves, furnaces and other heaters, and adapted to enable crude oil, refined oil, or alcohol and the like to be employed as fuel, and capable of converting the same into a gas and of entirely consuming the latter.

20 A further object of the invention is to provide a stove of this character in which the degree of heat may be readily controlled by the flow of the fuel to the burner and in which the fuel will be caused to spread over 25 the burner in a thin sheet, whereby the entire fuel delivered to the burner will be converted into a gas and all danger of clogging the burner thereby eliminated.

With these and other objects in view, the 30 invention consists in the construction and novel combination of parts hereinafter fully described, illustrated in the accompanying drawing, and pointed out in the claims here-to appended; it being understood that various changes in the form, proportion, size 35 and minor details of construction, within the scope of the claims, may be resorted to without departing from the spirit or sacrificing any of the advantages of the invention.

40 In the drawing: Figure 1 is a central vertical sectional view of an oil gas burner, constructed in accordance with this invention. Fig. 2 is a plan view of the upper 45 burner plate. Fig. 3 is a similar view of the lower tray.

Like numerals of reference designate corresponding parts in all the figures of the drawing.

50 In the accompanying drawing in which is illustrated the preferred embodiment of the invention, the burner comprises in its

construction a top burner plate 1, and a lower tray 2 designed to be constructed of cast iron or other suitable material and ad- 55 justably mounted on a vertical branch or portion 3 of a supply pipe 4, which extends to a suitable source of liquid fuel supply, the flow of the latter to the burner being controlled by a needle valve 5 of the ordinary construction. The fuel supply pipe preferably consists of an inch pipe, but the diameter of the pipe and the size and shape of the burner plate and the tray may, of course, be varied to suit the character of 60 the stove, furnace or other heater to which the burner may be applied.

The upper portion of the vertical branch 3 of the supply pipe is provided with exterior screw threads 6, and the burner plate 70 1, which is preferably in the form of a horizontally disposed disk, is provided with a central threaded opening 7, and is screwed on the upper end of the vertical branch 3. The burner plate, which is imperforate 75 from the central opening to its periphery, is provided in its upper face with a radially tapering recess 8 gradually increasing in depth from the central opening to an outer vertical annular marginal or peripheral wall 80 9, formed by recessing the upper face of the burner plate and located at the periphery of the same. The burner plate has a beveled outer edge or peripheral face 10, which inclines upwardly and inwardly 85 from the lower edge of the burner plate, and the lower face of the latter is provided with a recess 11, having an outer downwardly and outwardly inclined peripheral wall 12 to enable the burner plate to constitute a hood and adapted to hold the heat and flame in starting the burner, and capable also of deflecting the air downwardly 90 in the direction of the lower tray 2 in the operation of the burner. The oil or other liquid fuel is adapted to spread out in a thin sheet over the upper face of the burner plate as it flows from the supply pipe 3, and after the burner plate becomes heated such fuel will be immediately converted into 95 gaseous form and burn. The recess 8 is designed to retain such fuel on the upper face 100 of the burner plate until converted into a gas, but if it is desired to increase the heat-

ing effect of the burner, the needle valve is opened to permit an increased supply of fuel to cause the oil or other fuel to flow over the wall 9 onto the tray 2, the inclined 5 peripheral face 10 being adapted to direct the liquid fuel upon the tray 2.

Any number of lower trays may be employed to provide a burner of the desired capacity, and the said lower tray 2, which 10 is disposed horizontally, is of greater diameter than the burner plate and consists of a central hub portion or ring 13, radial arms 14 and an outer rim or annular body portion 15, provided in its upper face with an annular recess or gutter 16 increasing in depth outwardly and forming an outer upwardly extending wall 17. The annular groove or gutter is located beneath the lower peripheral edge of the burner plate and it is of 15 sufficient width to receive the liquid fuel flowing from the burner plate. The bottom face of the annular recess or gutter is inclined and extends downwardly from the inner edge or face of the rim 15 to the wall 20 17. The recess or gutter 16 is adapted to catch the liquid fuel flowing over the burner plate and it also serves as a starting receptacle in which oil may be burned to heat the burner plate in starting the burner. The 25 hub or ring 13 is provided with a threaded opening 18 and screws on the threaded portion of the vertical branch of the supply pipe being spaced from the top burner plate. The rim 15 of the tray 2 is provided in its 30 lower face with an annular groove 19 receiving the upper edge of a cylindrical air shaft 20, constructed of iron or other suitable material and consisting of a vertically disposed cylinder having imperforate walls 35 and arranged upon and extending upwardly from the grate 21 of the stove or other heater to which the burner is applied. The vertical branch of the fuel supply pipe extends upwardly through the grate, as shown 40 in Fig. 1 of the drawing, and the openings between the grate bars are sealed beyond the air shaft by fire clay, asbestos, or other non-combustible material as well as at the other openings in the fire box of the stove or 45 heater, so that the air for supporting combustion must pass upwardly through the air shaft to the burner. The air ascending the cylindrical shaft or flue 20 passes through 50 the openings or spaces between the arms 14 of the lower tray 2, and passes outwardly over the lower tray through the space between the same and the upper burner plate and is adapted to support combustion when 55 fuel is burned in the groove or gutter in starting the burner and also after the top burner plate has become heated sufficiently 60 to generate gas from the liquid fuel. When the fuel is burned in the groove or gutter to start the burner, the lower hood portion of 65 the burner plate is adapted to hold the heat

and flame so as to cause a rapid heating of the said plate and a quick starting of the burner. Crude oil, refined oil, alcohol or similar liquid fuel may be used in the burner, which is adapted to produce an 70 intense economical heat. In operating the burner, the fuel may be controlled so that after the starting of the burner, the burner plate will convert into a gas the entire amount of fuel fed to it. If the top disk 75 or burner plate does not furnish sufficient heat, the flow of fuel is increased to cause a portion of the same to be delivered to the lower tray where it will be converted into a gas and burn, the lower tray operating in 80 the same manner as the upper plate. By increasing the number of lower trays, a burner of any desired heating capacity may be obtained.

What is claimed is:—

1. The combination with a grate, of a vertical air shaft seated upon the grate and having imperforate vertical walls, a tray seated upon the upper edges of the vertical walls of the air shaft and provided in its upper face with a groove or gutter, a supply pipe passing through the grate and extending through and projecting above the tray, the latter being provided at an intermediate point between the supply pipe and the walls of the air shaft with openings, and a top burner plate mounted upon the upper end of the supply pipe and having an opening receiving the same, said supply pipe supporting the top 100 burner plate above and out of contact with the tray and the said burner plate having its periphery located in the vertical plane of the groove or gutter of the tray.

2. A burner of the class described including a vertical supply pipe, a top horizontally disposed burner plate having a central opening to receive the supply pipe and provided in its upper face with a recess increasing in depth outwardly and forming an upwardly projecting marginal wall, said burner plate being also provided in its lower face with a recess having an outer inclined wall extending downwardly and outwardly, the outer edge or face of the burner plate being inclined upwardly and inwardly, and a lower tray having a groove or gutter located beneath and spaced from the outer edge of the burner plate and adapted to receive fuel therefrom.

3. A burner of the class described including a vertical air shaft open at the top and bottom and having imperforate walls and designed to be arranged within the fire pot of a stove or heater, a lower horizontal tray having a recess or gutter in its upper face and provided in its lower face with a groove receiving the upper edge of the air shaft, a fuel supply tube passing through the air shaft and through the lower tray and ex-

tending above the latter, and a top burner plate spaced from the lower tray and having an opening receiving the supply pipe, said burner plate extending outwardly 5 therefrom to a point above the groove or gutter of the lower tray.

In testimony, that I claim the foregoing

as my own, I have hereto affixed my signature in the presence of two witnesses.

WALTER R. THATCHER.
